US0D1040789S

(12) **United States Design Patent** (10) **Patent No.:** **US D1,040,789 S**
(45) **Date of Patent:** **** Sep. 3, 2024**

(54) **MICROPHONE POP FILTER**

(71) Applicant: **Enping Aopo Electronic Technology Co., Ltd.**, Enping (CN)

(72) Inventor: **Zhenping Liang**, Enping (CN)

(73) Assignee: **Enping Aopo Electronic Technology Co., Ltd.**, Enping (CN)

(**) Term: **15 Years**

(21) Appl. No.: **29/939,633**

(22) Filed: **Apr. 29, 2024**

(51) LOC (14) Cl. **14-01**

(52) U.S. Cl.

USPC **D14/229**

(58) **Field of Classification Search**

(57) **CLAIM**

The ornamental design for a microphone pop filter, as shown and described.

DESCRIPTION

FIG. 1 is a front perspective view of a microphone pop filter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a rear perspective view thereof, in use.

The broken lines in the drawings illustrate the portions of the microphone pop filter, which form no part of the claimed design.

1 Claim, 9 Drawing Sheets
